(57) **CLAIM**

The ornamental design for a salmon pet treat, as shown and described.

DESCRIPTION

FIG. 1 is front, top and right side perspective view of a first embodiment of a salmon pet treat according to the new design;

FIG. 2 is a front, bottom and left side perspective view of the embodiment of FIG. 1;

FIG. 3 is a front view of the embodiment of FIG. 1;

FIG. 4 is a back view of the embodiment of FIG. 1;

FIG. 5 is a right side elevation view of the embodiment of FIG. 1;

FIG. 6 is a left side elevation view of the embodiment of FIG. 1;

FIG. 7 is a top plan view of the embodiment of FIG. 1;

FIG. 8 is a bottom plan view of the embodiment of FIG. 1;

FIG. 9 is front, top and right side perspective view of a second embodiment of a salmon pet treat according to the new design;

FIG. 10 is a front, bottom and left side perspective view of the embodiment of FIG. 9;

FIG. 11 is a front view of the embodiment of FIG. 9;

FIG. 12 is a back view of the embodiment of FIG. 9;

FIG. 13 is a right side elevation view of the embodiment of FIG. 9;

FIG. 14 is a left side elevation view of the embodiment of FIG. 9;

FIG. 15 is a top plan view of the embodiment of FIG. 9;

FIG. 16 is a bottom plan view of the embodiment of FIG. 9;

FIG. 17 is front, top and right side perspective view of a third embodiment of a salmon pet treat according to the new design;

FIG. 18 is a front, bottom and left side perspective view of the embodiment of FIG. 17;

FIG. 19 is a front view of the embodiment of FIG. 17;

FIG. 20 is a back view of the embodiment of FIG. 17;

FIG. 21 is a right side elevation view of the embodiment of FIG. 17;

FIG. 22 is a left side elevation view of the embodiment of FIG. 17;

FIG. 23 is a top plan view of the embodiment of FIG. 17; and,

FIG. 24 is a bottom plan view of the embodiment of FIG. 17. The evenly-spaced broken lines in the drawings illustrate portions of the salmon pet treat that form no part of the
